UNITED STATES PATENT OFFICE.

JOSEPH KELSO, OF PITTSBURGH, PENNSYLVANIA, ASSIGNOR TO McCONWAY & TORLEY COMPANY, OF PITTSBURGH, PENNSYLVANIA, A CORPORATION OF PENNSYLVANIA.

KNUCKLE-PIN RETAINER FOR CAR-COUPINGS.

1,021,464.

Specification of Letters Patent.

Patented Mar. 26, 1912.

Application filed April 14, 1911. Serial No. 621,066.

To all whom it may concern:

Be it known that I, JOSEPH KELSO, a citizen of the United States, residing at Pittsburgh, in the county of Allegheny and State 5 of Pennsylvania, have invented certain new and useful Improvements in Knuckle-Pin Retainers for Car-Couplers; and I do hereby declare the following to be a full, clear, and exact description of the invention, such 10 as will enable others skilled in the art to which it appertains to make and use the same.

My invention relates to the construction 15 of car couplers of the vertical plane type and is particularly directed to the provision of simple and efficient means for securely maintaining the knuckle pin in its normal position and for preventing the same from dropping out when broken, thus insuring 20 proper pivotal connection of the knuckle and coupler head when the coupler is in service.

To accomplish the before-noted objects a knuckle pin retaining member is detachably mounted upon the underside of the coupler head adjacent to the knuckle pin opening therein, the retaining member being so formed that one end thereof extends under the knuckle pin and the other end 30 thereof engages the coupler head, and such a construction embodies the principal feature of my invention.

In the drawings chosen for the purpose of illustrating my invention, the scope whereof 35 is pointed out in the claim, Figure 1 is a side elevation of a portion of a coupler provided with a knuckle pin retainer constructed in accordance with my invention; and Fig. 2 is an inverted plan view of the devices shown in Fig. 1, the knuckle, however, being omitted.

Like symbols refer to like parts wherever they occur.

I will now proceed to describe my invention more fully, so that others skilled in the art to which it appertains may apply the same.

In the drawings, 1 indicates the coupler head and 2 the knuckle, these two parts being pivotally connected in the usual manner 50 by means of a knuckle pin 3.

Projecting downwardly from the under side of the coupler head 1 and located adjacent to the pivot pin opening 4 therein is a supporting member 5 by means of which 55 the knuckle pin retaining member 6 is mounted upon the coupler head. This supporting member 5 is preferably formed as a perforated lug which is integral with the coupler head 1, the perforation being designed to receive a cotter pin 7 which passes through a similar perforation in the member 6 to thus secure the latter to the lug 5.

The knuckle pin retaining member 6 is preferably fashioned as a bar having end 60 portions 6^a and 6^b, respectively, which are in different planes, the portion 6^a, which is adapted to engage the under face of the coupler head, being higher than the opposite end portion 6^b which extends beneath and 65 preferably a slight distance below the lower end of the knuckle pin 3. When a cotter 7 is employed to attach the knuckle pin retaining member 6 to the coupler head the intermediate portion of the retaining member 70 should be somewhat enlarged, as at 6^c, in order that a cotter pin aperture may be formed therein and the strength of the part 75 be still maintained.

In order to prevent the knuckle pin 3 80 from moving upwardly and thus becoming disassociated from the coupler head 1 and knuckle 2, a cotter 8 may be passed through a transverse opening in the lower end of the knuckle pin in the usual manner.

Having thus described my invention, what I claim and desire to secure by Letters Patent is:

In a knuckle pin retainer for car couplers, the combination with the coupler head, 90 knuckle and knuckle pin, said coupler head being provided with a perforated lug on its lower face, of a knuckle pin retaining member which is formed with a horizontally ex-

tending pin receiving aperture intermediate of its length and with end portions which are in different planes, one of said end portions engaging the coupler head outside of 5 the knuckle pin receiving aperture therein and the other extending under the knuckle pin, and a pin passing through the aperture in the knuckle pin retaining member and

through the perforated lug on the lower face of the coupler head.

In testimony whereof I affix my signature, in the presence of two subscribing witnesses.

JOSEPH KELSO.
